DESIGN FOR A MAT OR SIMILAR ARTICLE

Thomas L. Leishman, New York, N. Y.

Application April 24, 1939, Serial No. 84,527

Term of patent 7 years

To all whom it may concern:

Be it known that I, Thomas L. Leishman, a citizen of the United States, residing at New York, in the county and State of New York, have invented a new, original, and ornamental Design for a Mat or Similar Article, of which the following is a specification, reference being had to the accompanying drawing, forming part thereof, wherein the figure is a plan view of a mat or similar article, showing my new design.

I claim:

The ornamental design for a mat or similar article, substantially as shown.

THOMAS L. LEISHMAN.
